**POWERPLANT TRANSMISSION ROTOR UNIT
FOR A HELICOPTER**

Peter J. Papadakos, Saint James, N. Y., assignor to Gyro-dyne Company of America, Inc., Flowerfield, N. Y., a corporation of New York

Application January 19, 1955, Serial No. 34,076

Term of patent 14 years

(Cl. D71—1)

Fig. 1 is a side perspective view of a powerplant transmission rotor unit for a helicopter, showing my new design.

Fig. 2 is a fragmentary top perspective view thereof, and

Fig. 3 is a top view of said unit with the rotor blades omitted for convenience of illustration only.

I claim:

The ornamental design for a powerplant transmission rotor unit for a helicopter, as shown.
